TOY RAILWAY TRACK SWITCH AND
METHOD OF MAKING SAME

Stephan Schaffan, Jr., Irvington, N. J.

Application September 5, 1941, Serial No. 409,637

3 Claims. (Cl. 246—415)

This invention relates to improvements in toy railway track switch and method of making same.

An object of my invention is to provide a method whereby a unitary, compact and highly durable track switch may be made from lengths of solid metal stock which are initially rolled to provide upstanding parallel rails, the stock being then cut into suitable lengths and the rails being then subjected to a tapered cutting operation, being finally subjected to an operation for the removal of transverse web material intermediate the rails leaving one or more transverse web portions which integrally connect the rail members in spaced, parallel relation. The switch unit is provided with an actuating switch arm secured thereto, preferably made of dielectric material.

These and other advantageous objects are accomplished by the simple and practical construction illustrated in the accompanying drawing, forming part hereof, and in which:

Fig. 1 is the top plan view of a section rolled to provide the rail members.

Fig. 2 is a similar view showing the section after it has been subjected to the tapered cutting operation,

Fig. 3 is a similar view showing the section after it has been subjected to the operation for removal of material of the web portion, leaving one or more transverse web portions integrally connecting the rail members in spaced, parallel relation,

Figs. 4, 5 and 6 are transverse vertical sectional views taken on lines 4—4, 5—5, and 6—6 of Figs. 1, 2 and 3, respectively, in the direction indicated by the arrows,

Fig. 7 is a top plan view of a toy railway track system embodying the switch of my invention,

Fig. 8 is a fragmentary transverse vertical sectional view taken on line 8—8 of Fig. 7 in the direction of the arrows,

Fig. 9 is a bottom plan view of the railway track switch shown in Fig. 3.

A preferred embodiment of the invention is described in the following specification while the broad scope of the invention is pointed out in the appended claims.

Referring to the drawing, in Figs. 1 and 4 there is shown a length 10 of stock which has been rolled to provide upstanding parallel rails 11 and 12 integrally connected by the transverse web 13. In Fig. 2 the switch has been subjected to the second step in my method, namely a tapered cutting operation initiated at the end 14 of the rail section, the tapering effect being toward the end 15.

In Figs. 3, 6 and 9 the switch is shown after the third step in my method wherein the web 13 except for transverse web portions 16, 17 and 18 is removed by a stamping or similar operation, leaving the rails 11 and 12 integrally connected in spaced parallel relation by the said transverse web portions 16, 17 and 18.

The switch unit is provided with an actuating arm 19 (Fig. 8) secured thereto in any desired or convenient manner, preferably by a pivot member 20 passed through an aperture A struck out of the medial portion 17 and flared over the web portion 17 and switch arm 19 to pivotally secure the parts together.

In Fig. 7 there is shown a top plan view of a miniature railway track system in which the rails 11 and 12 of the switch unit are adapted to continue the fixed rails 23 and 24 on to the rails 21 and 22. Any desired or convenient means (as pins 30 on the ties T) complementary to the switch unit may be provided to enable the latter to be shifted into abutment with either of the outer rails 21 or 22. As will be noted from Fig. 7, the outer rails 21 and 22 are recessed at their inner faces 25 and 26 to snugly receive the corresponding forward ends of the rails 11 and 12 so that when the latter are moved into abutment with the outer rails 21 and 22 they will neatly cooperate therewith to present complete rail faces for the support of the trains.

As will be noted from Figs. 7 and 8, in the assembled position of the switch of my invention, the switch arm 19 will underlie the switch unit, resting on the outer rails 21 and 22 intermediate adjacent ties T thus serving to effectively position the switch unit so that it may be readily manually transversely shifted into either of its operative positions. Thus the ties T intermediate which the switch arm 19 is positioned guide the latter in its transverse shifting in use, the pivot member 20 enabling the forward end 15 of the switch unit to pivotally accommodate itself out of parallel relation to arm 19 as necessary to effect its shifting as shown in Fig. 7. The arm 19 may be of dielectric material when the switch unit is to be used in electric track systems. As set forth above, any suitable means, as pins 30 on the tie T providing a pivot bearing for the other end 14 of the unit 10, may cooperate to facilitate the described shifting action.

While I have found the use of metals especially desirable in the construction of a railway track switch pursuant to the teachings of my invention, and have found in practice that ferrous metals are best suited for this purpose, my in-

vention is equally adapted for use in connection with any other metals and plastics or other materials. I have not particularly set forth the means for securing the rails 21, 22, 23 and 24 to the ties T as any conventional securing means may be employed for this purpose.

My invention may be used with equal efficacy in connection with electric and non-electric track systems. When used with electric systems, any desired or convenient means may be provided for insulating the various parts of the track system and switch unit with appropriate circuits and means for initiating, maintaining and discontinuing the flow of current as desired.

Having thus described my invention, what I claim as new and desire to secure by Letters Patent, is:

1. In a toy railway track system, a plurality of ties arranged in spaced, parallel relation, a pair of outer rails secured to said ties in spaced relation, a pair of converging rails secured to said ties intermediate said outer rails, and a switch unit slidably arranged on said ties intermediate said outer rails, and forwardly adjacent said converging rails, said unit comprising a pair of parallel, upstanding rails with spaced transverse web portions integrally connecting the same adjacent the forward ends thereof, said pair of rails and connecting webs being of solid cross section, a switch arm pivotally secured to one of said transverse web portions, said switch arm being positioned beneath the outer rails and intermediate a pair of adjacent ties, the transverse web portions and switch unit rails being positioned intermediate the outer rails to enable the switch unit to be transversely shifted into abutment with either of the outer rails on actuation of the switch arm, said switch arm being guided during said shifting movement by the pair of ties intermediate which the arm is positioned, and means arranged on one of the ties located adjacent the rear end of the switch unit for cooperation with one of the rails of the unit to serve as a fulcrum for the rear end of the unit and to permit limited shifting of the unit into cooperative relation with the forward ends of the second mentioned pair of rails, when the switch arm is actuated.

2. In a toy railway track system, a plurality of ties arranged in spaced, parallel relation, a pair of outer rails secured to said ties in spaced relation, a pair of converging rails secured to said ties intermediate said outer rails, and a switch unit slidably arranged on said ties intermediate said outer rails, and forwardly adjacent said converging rails, said unit comprising a pair of parallel, upstanding rails with spaced transverse

web portions integrally connecting the same adjacent the forward ends thereof, said pair of rails and connecting webs being of solid cross section, a switch arm pivotally secured to one of said transverse web portions, said switch arm being positioned beneath the outer rails and intermediate a pair of adjacent ties, the transverse web portions and switch unit rails being positioned intermediate the outer rails to enable the switch unit to be transversely shifted into abutment with either of the outer rails on actuation of the switch arm, said switch arm being guided during said shifting movement by the pair of ties intermediate which the arm is positioned, and means arranged on one of the ties located adjacent the rear end of the switch unit for cooperation with one of the rails of the unit to serve as a fulcrum for the rear end of the unit and to permit limited shifting of the unit into cooperative relation with the forward ends of the second mentioned pair of rails, when the switch arm is actuated.

3. In a toy railway track system, a plurality of ties arranged in spaced, parallel relation, a pair of outer rails secured to said ties in spaced relation, a pair of converging rails secured to said ties intermediate said outer rails, and a switch unit slidably arranged on said ties intermediate said outer rails, and forwardly adjacent said converging rails, said unit comprising a pair of parallel, upstanding rails with spaced transverse web portions integrally connecting the same adjacent the forward ends thereof, said pair of rails and connecting webs being of solid cross section, a switch arm secured to one of said transverse web portions, said switch arm being positioned beneath the outer rails and intermediate a pair of adjacent ties, to be guided therebetween, the transverse web portions and switch unit rails being positioned intermediate the outer rails to enable the switch unit to be transversely shifted into abutment with either of the outer rails on actuation of the switch arm, and means in said system cooperating with one of the rails of the rear end of the unit serving as a fulcrum for the rear end of the unit and to permit limited longitudinal shifting of the unit into aligned cooperative relation with the forward ends of the second mentioned pair of rails, when the switch arm is actuated.
